UNITED STATES PATENT OFFICE

ALFRED T. FLOYD, JR., OF LITTLE ROCK, ARKANSAS, ASSIGNOR OF FORTY-NINE PER CENT TO ELMER R. SCOTT, OF LITTLE ROCK, ARKANSAS

MUFFLER FOR ENGINES

Application filed January 6, 1930. Serial No. 418,844.

My invention relates to improvements in mufflers for internal combustion engines, and generally to arrangements adapted to be connected with the exhaust of such engines.

5 The object of my invention is to provide an attachment for the exhaust pipe of engines that will absorb the energy of the exhaust gases so as to reduce the noise thereof to a minimum.

10 A further object of my invention is to provide means to permit the expansion of the exhaust gases to readily take place and to dispose of such gases without any back pressure into the exhaust pipe of the engine, and 15 to discharge said gases to atmosphere at a reduced temperature; and with these and other objects in view my invention consists of the parts and combination of parts hereinafter pointed out.

20 In the drawings:

Figure 1 is a central longitudinal sectional view of my improved muffler.

Figure 2 is a sectional view on the line 2-2, Figure 1, looking in the direction of 25 the arrows.

Figure 3 is a front elevation of one of the baffle plates.

Figure 4 is a sectional view on the line 4-4, Figure 1.

30 The reference numeral 5 designates the shell or body of the muffler, which may be corrugated as at 6 on its periphery, or may be provided with fins, the object of which is to facilitate heat radiation from the interior of the shell.

35 A conical chamber 7 is secured at the forward end of the body 5 terminating in a cylindrical end 8 designed for attachment to the exhaust pipe of the engine; said 40 cylindrical end 7 functioning as an expansion chamber for the exhaust gases, the walls of such expansion chamber being abrupt. To the rear end of the expansion chamber is secured an outwardly dished, or conical

45 like, plate 9 having an outturned flange 10 which is secured to the rear end of the expansion chamber, after which the chamber 7 is suitably secured in the forward end of the muffler body 5. The plate 9 is provided with a central opening surrounded by

an outturned flange 11. It will be noted that the taper of the plate 9 is less abrupt than that of the expansion chamber 7.

55 A cylindrical jet tube 12 is secured at one end to the flange 11 of the plate 9 and terminates at its other end in a flaring flange 13. I secure in this jet tube 12 a suitable number of baffle plates 14, for instance two in number which are given a substantially spiral shape from end to end designed to 60 give the gases from the chamber 7 a whirling motion, some of which gases pass from the tube 12 through ports 15 into the body 5 of the muffler, while other portions of the gases are discharged through the flaring end 65 13 of the tube into the body of the muffler, and pass into the axial tube or equalizing chamber 16 to be hereinafter referred to.

70 Suitable number of baffle plates 17 having flanges 18 at their periphery adapted to bear against the inner face of the body 5 are rigidly affixed to the equalization chamber, and after the desired number of these baffles have been fixed to the chamber 16, it, with assembled baffles, are slid 75 into the body 5 and positioned therein as shown in Figure 1. If desired, a suitable damper 19 may be placed in the equalizing chamber 16 and is provided with an operating rod 20.

80 To the rear end of the body 5 I secure by bolts 21, or otherwise, a conical end extension 24 which is provided with a rearwardly extending outlet tube 22. Screw threaded to the rear end of the equalizing 85 chamber 16 is a removable jet nozzle 23 which is of such diameter that when in position is spaced from the inner periphery of the sleeve 22 so that an annular space or orifice 25 is formed between it and the 90 juncture of the sleeve 22 and extension 24. The size of this orifice is governed by the size of the interchangeable jet 23.

95 The baffles 17 are provided with blades 26 which are struck up from the body of the baffles and extend rearwardly therefrom, as clearly seen in Figure 1.

100 The ports 15 are designed to be positioned in conformity with the angle and direction of the spiral plates 14.

In operation the exhaust gases enter the chamber 7 where they are permitted to expand and from which they pass into jet tube 12 in which the gases are given a whirling motion, and some of the gases pass direct into the equalization chamber 16, while others pass through the ports 15 into the second expansion chamber 27 with a whirling motion which further expands the force of the gases. The gases from the chamber 27 pass through the openings 28 in the baffles 17 and infringe upon the blades 26, and as the openings 28 in one baffle are staggered with reference to the next preceding baffle the gases are caused to flow from one baffle to the next in a whirling and spiral motion, which tends to still further dissipate the force of the gases while the heat is to a material extent radiated through the body 5 and its radiators.

The gases passing through the equalization chamber cause a suction in the tube 22 at the discharge end of the jet nozzle 23 which sucks the gases from the body 5 through the annular space 25, thus the exhaust gases are discharged from the sleeve 22 substantially cool and with a minimum of noise.

What I claim is:

1. In combination, in an engine exhaust muffler, a cylindrical body, an imperforated equalizing chamber extending longitudinally of and within said body and spaced therefrom, baffles between the body and said chamber, an expansion chamber at the forward end of said body, a second expansion chamber adjacent the first named expansion chamber, and a perforated cylindrical open ended jet nozzle, extending from the first expansion chamber into the second expansion chamber.

2. In combination, in an engine exhaust muffler, a cylindrical body, an imperforated equalizing chamber extending longitudinally of and with said body and spaced therefrom, baffles between the body and said chamber, an expansion chamber at the forward end of said body, a second expansion chamber adjacent the first named expansion chamber, and a perforate cylindrical open ended jet nozzle, extending from the first expansion chamber into the second expansion chamber, and in axial alignment with the equalizing chamber.

3. In combination, in an exhaust muffler for engines, a cylindrical body, an equalizing tube extending for a part of its length within said body, baffles disposed between the said tube and the inner face of the body, ports in each baffle staggered relative to the ports in a succeeding baffle, an expansion chamber in said body in advance of and in constant open communication with said tube, the forward baffle constituting the rear wall of said expansion chamber, means for

connecting the body to an exhaust pipe, an expansion chamber at the forward end of the body with which the forward end of said tube communicates and a cylindrical open ended perforate jet nozzle arranged between said second named expansion chamber and the said tube and projecting into the body immediately forward of and in axial alinement with said tube.

4. In combination, in an exhaust muffler for an engine, a cylindrical body, an equalizing tube extending for a part of its length within said body, baffles disposed between the tube and the inner face of said body, an expansion chamber in said body in advance of and in constant open communication with said tube, the forward baffle constituting the rear wall of said expansion chamber, a cylindrical perforate open ended jet nozzle extending into said expansion chamber in axial alignment with but spaced from the said tube, means for connecting said jet nozzle with an exhaust pipe of an engine, an expansion chamber at the forward end of the body with which said tube communicates and into which the said nozzle projects, and a tapered discharge nozzle at the rear end of said tube.

5. In combination, in an exhaust muffler for an engine, a cylindrical body, an equalizing tube extending for a part of its length within said body, ported baffles disposed between said tube and the inner face of the said body and having ports therethrough, the ports of one baffle being staggered relative to the ports of the next adjacent baffle, an expansion chamber in the forward part of said body, and in constant open communication with said tube, the forward baffle constituting the rear wall of said chamber, a second expansion chamber extending from the forward end of the said body and adapted for connection with the exhaust pipe of an engine, a third expansion chamber at the rear end of the body and in constant open communication with said tube, and a cylindrical perforate open ended jet nozzle opening at its rear end into the first-named expansion chamber and opening into the second-named expansion chamber with its rear end disposed adjacent to and in axial alinement with the forward end of the tube.

6. In combination, in an exhaust muffler for an engine, a cylindrical body, an equalizing tube extending for a part of its length within said body, spaced baffle disks disposed at right angles to the tube and body between said tube and the inner face of the said body, and having ports therethrough formed by portions displaced therefrom in a rearward direction, the ports of one baffle being staggered relative to the ports of the next adjacent baffle, an expansion chamber in the forward part of said body, and in constant open communication with said

5 tube, the forward baffle constituting the rear wall of said chamber, a second expansion chamber extending from the forward end of the said body and adapted for connection with the exhaust pipe of an engine, a third expansion chamber at the rear end of the body and in constant open communication with said tube, and a cylindrical perforate open ended jet nozzle opening at its rear 10 end into the first named expansion chamber and opening into the second-named expansion chamber with its rear end disposed adjacent to and in axial alinement with the forward end of the tube, and helical blades 15 in said nozzle.

6 7. In an engine exhaust muffler, a cylindrical body, primary and final expansion chambers at opposite ends of the body, an equalizing tube extending longitudinally of the body with its rear end extending into the final expansion chamber and its forward end disposed in rear of the primary expansion chamber, a series of spaced baffle disks disposed between and at right angles to the tube and body and having radially arranged ports therein, the ports of adjacent disks being staggered with relation to each other, an intermediate expansion chamber being formed in the body between the forward 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

drical body, primary and final expansion chambers at opposite ends of the body, an equalizing tube extending longitudinally of the body with its rear end extending into the final expansion chamber and its forward end disposed in advance of the primary expansion chamber, a series of spaced baffle disks disposed between and at right angles to the tube and body and having radially arranged ports therein, said ports being formed by rearwardly displaced portions of the disks, the ports of adjacent disks being staggered with relation to each other, an intermediate expansion chamber being formed in the body between the forward baffle disk and primary expansion chamber, a cylindrical perforate open ended jet nozzle communicating at its forward end with the primary expansion chamber and projecting into the intermediate expansion chamber with its rear end in proximity to and in alinement with the forward end of the tube, and helical blades in said nozzle.

7. In an engine exhaust muffler, a cylindrical body, primary and final expansion chambers at opposite ends of the body, a discharge outlet leading from the final expansion chamber, an equalizing tube extending longitudinally of the body with its rear end extending into the final expansion chamber and its forward end disposed in advance of the primary expansion chamber, a series of spaced baffle disks disposed between and at right angles to the tube and body and having radially arranged ports therein, said ports being formed by rearwardly displaced portions of the disks, the ports of adjacent disks being staggered with relation to each other, an intermediate expansion chamber being formed in the body between the forward baffle disk and primary expansion chamber, a cylindrical perforate open ended jet nozzle communicating at its forward end with the primary expansion chamber and projecting into the intermediate expansion chamber with its rear end in proximity to and in alinement with the forward end of the tube, and helical blades in said nozzle, and a tapered discharge nozzle at the rear end of the tube extending into the discharge outlet of the final expansion chamber in spaced relation thereto.

In testimony whereof I affix my signature.
